WILLIAM T. PHILLIPS AND THOMAS C. DE LISLE, OF LOS ANGELES, CALIFORNIA.

DISPLAY DEVICE.

1,157,252.

Specification of Letters Patent.

Patented Oct. 19, 1915.

Application filed July 7, 1914. Serial No. 849,623.

To all whom it may concern:

Be it known that we, WILLIAM T. PHILLIPS and THOMAS C. DE LISLE, citizens of the United States, residing at Los Angeles, in the county of Los Angeles, State of California, have invented new and useful Improvements in Display Devices, of which the following is a specification.

This invention relates to a device for displaying flexible articles of any and all characters; particularly for displaying rugs and the like.

The primary feature of our present invention is the handling of rugs or the like by suspension from their upper edges in much the same manner that rugs are handled by hand. To display rugs we move them from a vertical hanging position to a horizontal position where they may be viewed by a customer. In their vertical hanging position they occupy a relatively small space upon the floor.

The primary object of our invention is the provision of mechanism for handling the rugs in the manner set forth, and the provision of such a mechanism in simple reliable and inexpensive form, which may be easily applied for the purposes set forth and in which the rugs may be easily attached or taken out.

Details of our invention will become apparent from the accompanying drawings in which we have shown a preferred form of our mechanism and in which drawings,

Figure 1 is a vertical section of our improved machine, Fig. 2 is a front elevation thereof, Fig. 3 and Fig. 4 are enlarged details showing the action of the device in lowering rugs to the horizontal position, Fig. 5 is a section taken as indicated by line 5-5 of Fig. 3.

In the drawings the numeral 10 may designate a suitable base upon which the rugs 11 are laid when in their horizontal position. This base may be mounted upon any suitable frame work; and we may provide a back 12 against which the rugs may hang when in their vertical positions. The rugs are each hung upon suitable hangers 13, one for each rug. These hangers may consist preferably in elongated strips of thin metal 15 which may or may not extend along the whole of the top of the rugs; suitable teeth 16, or other means, being provided to secure the rug to the hanger strip 15. The hangers have suitable extensions 17 which

extend over the rug carrying arches 18 and over the chain carriers 19, having apertures 20^a surrounding the arches 18 in such manner that the rug carriers bear at 21 upon the arches 18 so that the arches carry the whole weight of the rugs. We prefer to provide three of these arches in order to successfully carry heavy rugs of large size, although any number can be provided. It is desired that the arches 18 carry all the weight of the rugs and that the chain carriers 19 be used only to guide the chains 20, the function of the chains being merely to move the rugs by proper engagement with the hangers 13; but this arrangement may be varied, especially where light articles are displayed and no great weight must be carried.

In their normal positions, the rugs hang as shown in Fig. 1 in vertical positions against the back 12. The arches 18 extend forwardly and downwardly to the forward edge of the base 10; and the curve of the arches is such that when the upper edge of a rug is moved forwardly and downwardly along the arches the rug will be laid out upon the base 10 much in the same manner as a rug is laid upon the floor by hand. The chain carriers 19 parallel the arches 18; and we prefer to have one chain carrier and one chain for each of the arches, although this may be arranged otherwise if desired. The chain carriers are preferably in the form of channels or the like and the chains 20 may be provided with rollers 30 so that they will move with minimum frictional resistance through the channel carriers 19 and over the various sprockets of the machine. Each of the chains 20 is endless and passes over a sprocket 31 at the bottom of the carrier 19, thence rearwardly to another sprocket 32 at the bottom of back 12 and thence may pass upwardly over an idler sprocket 33 and thence downwardly over a sprocket 34 and then upwardly to the sprocket 35 at the rear of the upper end of the chain carrier 19. The idler sprocket 33 is placed somewhat in the position shown in order to make a sufficient length of chain so that the two dogs 36 on each chain may be spaced apart by the distance illustrated and so that the endless length of chain is equally divided by the two dogs. A motor or other prime mover 37 may suffice to drive the whole system in either direction. The motor may be a reversible motor so that the chains may be

driven either direction at will. It will be noted that the dogs are spaced so far apart that only one rug is engaged by them at one time; one set of dogs will drop one rug before the next set picks up the succeeding one. The machine may be reversed when either of the dogs are engaging a rug.

The essentials of operation of our device are as follows:—Suppose that the rugs are all in their upright positions and it is desired to lower them to horizontal positions. The motor is started to move the chains in the direction indicated in the various views. The dogs 36 will engage the outermost rug hanger 13 and will carry that hanger and its rug 11 down to a horizontal position, laying that rug out on the base in the manner hereinbefore noted. After the first rug has been laid in its horizontal position, the next set of dogs will engage the next rug; and so on until all the rugs are laid in horizontal positions. It will be noted that any rug is fully laid down before the next succeeding rug is engaged by the dogs, owing to the fact that there is sufficient length of chain between the dogs so that one set will have reached the position where a rug is laid down before the succeeding set reaches position to engage the next rug. If it is desired to replace the rugs in their vertical positions, it is only necessary to reverse the travel of the chains, when the rugs will be picked up successively and moved from their horizontal positions to their original vertical positions; the dogs engaging the rug hangers one by one and moving them to, and dropping them in their correct positions on the upper parts of the supporting arches 18. To keep the rear edges of the rugs in horizontal position from being rolled or curled over by the dragging of successive rugs forwardly over them, we provide tapes 50 which are permanently attached at one end to the frame at 51 and releasably attached in any suitable manner to the rear lower edges of the rugs at 52. These tapes are of suitable graduated lengths to be pulled tight when the respective rugs are laid horizontally, the tapes thus limiting the forward movement of the rear edges of the rugs and preventing the rear edges from being dragged forward by the forward drag of a succeeding rug.

The manner in which the dogs 36 engage the rug hangers and disengage them will be now explained. As hereinbefore stated, each of the rug hangers bear directly upon the arches 18, so that none of the weight is borne by the chain carriers 19. Each of the extensions 17 of the rug hangers has an opening 40 surrounding the chain carrier 19 without engaging the chain carrier; and the chain will pass continuously through the openings 40 in these hangers as long as the machine is running. The dogs 36 are

shaped as is best shown in Figs. 3 and 4 and are mounted upon studs or pivots 41 with springs 42^a acting upon the dogs tending to normally throw them to positions at right angles to the chain; that is, upwardly and to the left from the position shown in Fig. 3. Entry of the dogs into the apertures 40 of the rug hangers tends to throw them back into either one direction or the other depending upon which direction the chains are traveling. Supposing that the chains are traveling in the directions indicated in Figs. 3 and 4. We have shown in these figures the relations of the various parts to illustrate how the dogs pick up a rug and engage its hanger 13 to lower it to the horizontal position and how the rug is finally dropped in the horizontal position. Each of the dogs has a notch 42 in each of its opposite edges, and immediately adjacent each of these notches is a raised portion 43, which raised portion is normally pressed against the edges of apertures 40 in the hangers 13 by the action of spring 42^a. In Fig. 3 the dog 36 has a tendency to move upwardly and is held down by the part 43 engaging with the hangers 13. When the dog has moved to the left in that figure to a position where its notch 42 comes under the hanger 13 farthest to the left, then the dog 95 may spring upwardly and the notch 42 will engage with the hanger and the hanger will immediately start moving to the left with the dog, moving forwardly and downwardly along the arches 18 until the rug attached 100 to the hanger is laid out flatly upon the base 10. This condition may be seen from consideration of Fig. 4. When the lowermost rug is laid down it will be seen that just as the rug and its hanger 13 reaches the final 105 position, the part 43 of the dog 36 will engage with the edge 10^a of the base 10 (or any other suitable member may be provided) and the upper end of the dog will be forced to the right of Fig. 4 so that its notch 42 110 will disengage the hanger and allow the dog to pass onwardly with the chain while the hanger remains in the position shown. The next hanger and rug will be brought down in the same manner and laid upon the 115 first rug, and so on until all the rugs are laid down or until the operation of the machine is reversed. In Fig. 4 we have shown a dog 36 in position just as it is about to disengage one of the hangers 13. To always 120 maintain a certain space between the hangers, we may provide suitable spacing lugs or bosses 13^a upon the hangers, these lugs providing that there shall always be sufficient space between the hangers so that the end 125 36^a of the dogs 36 may freely move between the hangers to engage the last one which the dogs pass. These bosses also form a means of accurately spacing the hangers so that the machine is accurate and trustworthy in 130

its action. In the drawings the space between the rugs is exaggerated for clarity of illustration; in practice we propose to make the hangers little if any thicker than the 5 rugs so that the rugs may rest practically against each other in either their vertical or horizontal positions. In moving the rugs back to their vertical positions, the action of the dogs is the same as described, excepting that the dogs are forced back to 10 positions opposite those shown in Figs. 3 and 4, and the uppermost rug hanger on the horizontal pile is picked up and dropped in correct position on the upper part of the 15 arches 18.

Having described preferred forms of our invention, we claim:

1. A device of the character described for displaying flexible articles, comprising a 20 horizontal display base, arch supports extending from one edge of said base to points above the opposite edge of the base, hangers adapted to travel along said arch supports and adapted to each support one of said 25 articles, the hangers being normally in position on the higher parts of said arches so that the articles are normally vertically suspended over the edge of the base, and means to move the hangers one by one along the 30 arches to their lower ends, the contour of the arches and travel of the hangers being such that the articles are laid out flat upon the base in the manner described.

2. A device of the character described for displaying flexible articles, comprising a 35 horizontal display base, arch supports extending from one edge of said base to points above the opposite edge of the base, hangers adapted to travel along said arch supports and adapted to each support one of said 40 articles, the hangers being normally in position in the higher parts of said arches so that the articles are normally vertically suspended over one edge of the base, and means 45 to move the hangers one by one along the arches to their lower ends, said means including endless flexible members paralleling the arches, and hanger engaging means in said flexible members, the contour of the 50 arches and travel of the hangers being such that the articles are laid out flat upon the base in the manner described.

3. A device of the character described, 55 comprising a horizontal display base, a vertical frame rising at one edge of the base, rug supporting arches reaching from the upper part of the vertical frame to the opposite edge of the display base, said arches having substantially horizontal portions 60 near the vertical frame, rug hangers normally resting upon the horizontal upper portions of the arches adjacent each other parallel to the said frame so that rugs supported from said hangers will hang vertically against each other, flexible chains par-

alleling the arches, means to move said chains longitudinally, and dogs pivotally mounted on the chains and adapted to engage the hangers one at a time.

4. A device of the character described, 70 comprising a horizontal display base, a vertical frame rising at one edge of the base, rug supporting arches reaching from the upper part of the vertical frame to the opposite edge of the display base, said arches having substantially horizontal portions 75 near the vertical frame, rug hangers normally resting upon the horizontal upper portions of the arches adjacent each other parallel to the said frame so that rugs supported from said hangers will hang vertically against each other, flexible chains paralleling the arches, means to move said chains longitudinally, 80 and dogs pivotally mounted on the chains and adapted to engage the hangers one at a 85 time, said dogs each having a notch adapted to engage a hanger and having a projection adapted to engage an adjacent hanger to prevent the notch from engaging the one hanger.

5. A device of the character described, 90 comprising a horizontal display base, a vertical frame rising at one edge of the base, rug supporting arches reaching from the upper part of the vertical frame to the opposite edge of the display base, said arches having substantially horizontal portions 95 near the vertical frame, rug hangers normally resting upon the horizontal upper portions of the arches adjacent each other parallel to the said frame so that rugs supported from said hangers will hang vertically against each other, flexible chains paralleling the arches, means to move said chains longitudinally, 100 and dogs pivotally mounted on the chains and adapted to engage the hangers one at a time, said dogs each having a notch adapted to engage a hanger and having a projection forward of the notch in the direction of movement of 105 the chain and dog, said projection adapted to engage an adjacent hanger and prevent the notch from engaging the one hanger, whereby the notch can only engage the outermost one of the assembly of hangers.

6. A device for displaying flat articles, 110 comprising a horizontal display base, means for normally suspending said articles from their upper edges in vertical positions above one edge of the base, a guide extending from 115 the normal elevated position of said upper edges to a lower point at the opposite edge of the base, and means to move the upper edges of said articles along said guide from their normal positions to lower positions at 120 the opposite edge of the base, the contour of the guide and the line of movement being such that the suspended articles first engage the base with their lower edges and are then 125 laid out flat on the base.

4

7. A device for displaying flat articles, comprising a horizontal display base, means for normally suspending said articles from their upper edges in vertical positions above one edge of the base, a guide extending from the normal elevated position of said upper edges to a lower point at the opposite edge of the base, and means to move the upper edges of said articles along said guide from their normal positions to lower positions at the opposite edge of the base, the contour of the guide and the line of movement of said upper edges being a continuous curve whose radius from the first mentioned edge of the base is continuously greater as the lower end of the guide is approached, so that the lower edges of the articles may be first laid on the base at the first mentioned edge and then gradually pulled toward the opposite edge as the whole of the article is laid on the base in the manner described.

8. A device for displaying flat articles, comprising a horizontal display base, means for normally suspending said articles from their upper edges in vertical positions above one edge of the base, a guide extending from the normal elevated position of said upper edges to a lower point at the opposite edge of the base, means to move the upper edges of said articles along said guide from their normal positions to lower positions at the opposite edge of the base, the contour of the guide and the line of movement of said upper edges being a continuous curve whose radius from the first mentioned edge of the base is continuously greater as the lower end of the guide is approached, so that the lower edges of the articles may be first laid on the base at the first mentioned edge and then gradually pulled toward the opposite edge as the whole of the article is laid on the base in the manner described, and means to limit the movement of the lower edges of the articles over the base away from the first mentioned edge.

9. A device for displaying flat articles comprising a horizontal base, a guide extending from a position elevated above one edge of said base to a lower position at the opposite edge of said base, and means for

moving the upper edges of said articles along the guide, the contour of the guide and movement of said upper edges being such that as said upper edges are moved downwardly along the guide the articles first engage the base with their lower edges and are then laid out flat on the base.

10. A device for displaying flat articles, comprising a horizontal base, means for suspending said articles from their upper edges in vertical positions above one edge of the base, means for engaging and moving the upper edges of said articles from their said positions to lower positions at the opposite edge of said base, and means for supporting and guiding said article moving means in such a line of movement that as the articles are moved downwardly along the guides they first engage the base with their lower edges and are then laid out flat on the base.

11. A device for displaying flat articles, comprising a horizontal display base, means for suspending the articles by their upper edges at one edge of the base at a height approximately equal to the vertical length of the articles, so that the lower edges hang near said edge of the horizontal display base, and means for moving the upper edges of said articles downwardly and horizontally to a point at the opposite edge of the horizontal display base.

12. A device for displaying flat articles, comprising a horizontal display base, means for suspending the articles by their upper edges at one edge of the base at a height approximately equal to the vertical length of the articles, so that the lower edges hang near said edge of the horizontal display base, and reversible means for moving the upper edges of said articles between their said positions and lower positions at the opposite edge of the horizontal display base.

In witness that we claim the foregoing we have hereunto subscribed our names this 1st day of July 1914.
